CLAIM

The ornamental design for a handset, as shown and described.

DESCRIPTION

FIG. 1 is a front view of a handset according to the new design.

FIG. 2 is a right side view of the handset shown in FIG. 1.

FIG. 3 is a top view of the handset shown in FIG. 1.

FIG. 4 is a bottom view of the handset shown in FIG. 1.

FIG. 5 is a rear view of the handset shown in FIG. 1.

FIG. 6 is a left side view of the handset shown in FIG. 1.

FIG. 7 is a rear view of a second embodiment of a handset according to the new design.

FIG. 8 is a left side view of the handset shown in FIG. 7.

FIG. 9 is a front view of the handset shown in FIG. 7.

FIG. 10 is a right side view of the handset shown in FIG. 7.

FIG. 11 is a top view of the handset shown in FIG. 7; and,

FIG. 12 is a bottom view of the handset shown in FIG. 7.

The broken lines shown in the second embodiment are directed to environment, superimposed on a continuous surface, and are for illustrative purposes only; the broken lines form no part of the claimed design in the embodiment in which they are shown.

It is certified that error appears in the above-identified patent and that said Letters Patent is hereby corrected as shown below:

Title page, item [30]

Under Foreign Application Priority Data, Chinese Patent Application No. "2007 3 0131488" should be --200730131488.2--

Before the Claim the following paragraphs should appear:

This design application is related to co-pending design application number 29/282,636, entitled "Handset" filed on July 25, 2007.

To All Whom It May Concern:

Be it known that we, Bin Su, Yun Mo and Zhiyan Yang, have invented a new, original and ornamental design for a HANDSET, for which the following is a specification, reference being had to the accompanying drawings, forming a part hereof:
